TYPEWRITING MACHINE

Joseph Phelps, Herkimer, N. Y., assignor to Remington Rand Inc., New York, N. Y., a corporation of Delaware

Application January 31, 1934, Serial No. 709,179

8 Claims. (Cl. 197—60)

My invention relates to typewriting machines and more particularly to means for effectively supporting the carriage in the rear of the printing point to resist or counteract the pressure exerted on the platen by the type bars, without, however, offering any material resistance to the travel of the carriage or its case shifting movements.

To the above and other ends which will hereinafter appear, my invention consists in the features of construction, arrangements of parts and combinations of devices set forth in the following description and particularly pointed out in the appended claims.

15 In the accompanying drawings, wherein like reference characters indicate corresponding parts in the different views—

Fig. 1 is an enlarged, detail, fragmentary, fore and aft vertical sectional view of a portion of the machine, showing the features of my invention embodied therein.

Fig. 2 is an enlarged, detail, rear elevation showing some of the parts disclosed in Fig. 1 and with parts in section and parts broken away.

25 Fig. 3 is a transverse, horizontal sectional view of the parts shown in Fig. 2, the section being taken on the line 3—3 of Fig. 2 and looking in the direction of the arrows at said line.

Fig. 4 is a side view with parts in section and showing the connections between the manually controlled adjusting device and some of the parts controlled thereby.

30 Fig. 5 is a front view of said manually controlled adjusting device and some of the associated parts.

Fig. 6 is a view which shows in perspective various parts detached from one another and which enter into the construction of the present invention.

40 Fig. 7 is a detail, perspective view of the carrier for the anti-friction rollers as seen from the rear and.

Fig. 8 is a detail, fragmentary front elevation with parts in section of the sliding support for the carriage and some of the associated parts.

The features of the present invention are shown embodied in the latest model No. 6 Remington noiseless machine for which they were specially designed and in which they may be readily embodied without otherwise modifying or materially modifying other structural features of said machine. It should be understood, however, that the invention is not restricted to embodiment in such machines but may be included

in typewriting and like machines generally, wherever found available.

In the No. 6 Remington noiseless machine it has been found desirable to extend a support from the frame of the machine up in the rear 5 of the platen to resist the approximately eighteen pound pressure exerted by each type bar against the platen. One of the main objects of my present invention is to provide an effective support of this character and also provide means that 10 afford an easy relative travel and case shifting movements between the carriage and said support with which it coacts. The construction is such, moreover, that a bodily adjustment of such support and carriage may be readily effected as 15 a single unit fore and aft of the machine with the aid of an easily accessible, manually controlled adjusting device.

Referring more particularly to Fig. 1 it will be seen that a cylindrical platen 10 is carried by a carriage to travel across the machine, the side plates of said carriage being indicated at 11. These side plates are connected by cross bars 12, 13 and 14, the bar 13 being detachably secured to the carriage by screws 13a. The cross bar 20 14 is provided with raceways 15 in the opposite edges thereof to receive crossed bearing rollers 16 that likewise receive a bearing in the oppositely grooved rails 17 and 18 that constitute the usual support on which the carriage travels in 25 its movement from side-to-side of the machine.

The united rails 17 and 18 are in the lattice of a case shift frame and are provided with depending lugs 19 to which are pivoted, at 20, rearwardly extending case shift arms 21. From a 30 consideration of Figs. 1 and 8 it will be seen that each of these arms is adjustably connected by two screws 22, to an arm 23 formed integral with a rock shaft 24. This shaft is mounted at its ends on bearing screws 25 (Fig. 8) in upstanding 35 lugs 26 that project from a slidably mounted support 27. The arms 23 are under control of the usual case shift keys (not shown) to effect a case shifting movement of the carriage and the platen carried thereby.

The sliding support 27 extends from side-to-side of the machine and is supported at its ends on bearing members 28 of a cross bar X that extends from side-to-side of the machine and is fixed to lugs 29 on the side plates 30 of the 40 frame by screws 31. Retaining blocks 32 overlap the sliding support 27 at the ends thereof to prevent upward displacement of the sliding member, said retaining blocks being held in place by screws 33. The sliding support 27 has 45 50 55

integral depending bearing members 34 near the center thereof. These members are received between and are guided against lateral displacement by upstanding parallel guide members 35 5 on the fixed cross bar X. The lower ends of the members 34 are supported and have a sliding bearing fore and aft of the machine on the cross bar X.

In order to effect a fore and aft adjustment of 10 the sliding support 27 and the parts connected therewith I have provided the usual manually controlled adjustable finger piece 36 (Figs. 4 and 5) in a convenient location for manipulation by the operator, the finger piece in the present instance being located in the front of the machine. 15 This finger piece is carried at the free end of a crank arm 37 fixed by a screw 38 to an interiorly threaded sleeve 39 mounted to turn freely in a bearing in the front plate 40 of the frame. 20 The head of the sleeve 39 and the coacting rear side of the arm 37 are serrated to hold these parts to turn together. A screw 41 is received in a tapped opening in the sleeve 39 so that a turning of the sleeve will effect a forward or rearward 25 adjustment of the screw 41 and the parts connected therewith. The screw 41 is bifurcated at its rear end to receive the forward end of a link 42 which is pivoted to the screw at 43. The rear end of this link is pivoted at 44 to an upstanding 30 projection 45 on the sliding support 27 and located about midway in the length thereof. These parts for adjusting the carriage are substantially the same as those heretofore employed in the No. 6 Remington noiseless machine.

35 From the foregoing description it will be understood that the entire carriage may be adjusted forward or rearward depending on the direction in which the finger piece 36 is adjusted and that the effect of this is to vary the platen relatively 40 to the printing faces of the type bars when the latter are projected to printing position under control of the usual toggles by which they are actuated. This compensates for the various thicknesses or numbers of work sheets that may 45 be employed in the machine.

In the present construction the slide 27 is provided with an extension comprising two parallel supporting members 46 that extend upward in the rear of the platen and in the rear of the printing 50 point indicated by the dotted line a in Fig. 1. This extension constitutes a support for the carriage at the place indicated to resist the backward thrust of the type bars against the platen.

In accordance with my present invention I 55 provide anti-friction rollers between the carriage and the rigidly held though adjustable support 46, as will now be described.

An upright slightly inclined metal guide plate 47 is fixedly secured by screws 48 to the supporting members 46. Anti-friction rollers 49, (five in the present instance) bear against the guide plate 47 and are arranged one above another with their axes horizontally disposed. These rollers at their ends are loosely disposed and guided in upright channels in an anti-friction roller carrier, designated as a whole by the reference numeral 50 and shown detached in Fig. 7. The channel at each end of the carrier which receives the rollers 49 is provided with an end wall 51 60 formed as a part of the body of the carrier and which prevents an endwise displacement of the rollers. A metal strap 52 is secured by screws 53 and 54 (Figs. 6 and 7) to the carrier 50 near each end thereof. Each strap forms an enclosure 65 70 and rear, top and bottom walls of the channels 75

in which the ends of the rollers 49 are received, said rollers bearing at one side against the upright rear wall 55 of the carrier 50 and at the other side against the guide plate 47. The anti-friction rollers 49 are provided to afford an easy 5 case shifting movement of the carriage relatively to the rear support 46 while at the same time providing an effective support for the carriage in the rear of the platen, as will hereinafter more 10 clearly appear.

In order to limit the downward movement of the rollers 49 I prefer to employ stops in the nature of brackets 49^b which are secured to the members 46 by screws 49^b as best shown in Fig. 2.

The front face of the carrier 50 has a horizontally disposed groove 56 therein which receives the rear edge portion of the cross bar 13 of the carriage with a loose fit, so that said bar is free to move longitudinally, or in the direction of the travel of the carriage, independently of the carrier. When, however, the carriage receives a case shifting movement the cross bar 13 will be shifted laterally therewith and will move the carrier 50 20 up or down therewith.

In order that the cross bar 13, and therefore 25 the carriage, may move freely in the direction of the travel of the latter, and without material friction against the relatively fixed carrier 50, I provide the latter with anti-friction rollers 57. The axes of the pivots 58 for these rollers are 30 upright or at right angles to the axes of the rollers 49. The rollers 57 are so disposed on the carrier 50 that the rear edge of the cross bar 13 will bear against them and maintain such edge free from contact with the rear wall of the groove 35 56. This enables the carriage to move independently of the carrier 50 and the support 46 to which it is operatively connected, as will presently appear, with little frictional resistance and yet provide an effective support for the carriage back of 40 the printing point.

In order that the anti-friction roller carrier 50 may be held relatively to the support 46 against movement in the direction of the travel of the carriage, I provide a holding bracket 59 that has 45 an upright slot 60 therein to receive a screw 61. A nut 62 and washer 63 clamp the bracket 59 in place against a second square nut 64 on said screw so that there is no frictional resistance between the bracket 59 and the guide plate 47 during the 50 case shifting movement of the carriage. The arm 65 of the bracket terminates in a depending portion 65^a and said arm and terminal portion pass through an upright slot 66 in the guide plate 47 and into a recess 67 in the upper edge of the carrier 50 and by engaging the side walls of said recess prevents the carrier from moving in the 55 direction of the travel of the carriage.

In addition to the anti-friction rollers 57 which 60 coat with the rear edge of the cross bar 13 I provide anti-friction rollers 68 which coat with the front edge of said cross bar. The rollers 68 are mounted on upright headed pivots 69 carried by a bracket 70. The upright foot piece of this bracket has a rectangular opening 71 therein 65 through which the screw 61 passes after first passing through an opening in a washer plate 71^a. The square nut 64 into which the screw 61 is threaded fits and is received in the opening 71 which prevents the nut from turning. Located 70 between the rollers 68 is a headed pin 72 which is out of contact with the cross bar 13, but the head of which pin overlaps the top of said cross bar.

From the foregoing description it will be un- 75

derstood that a case shifting movement of the carriage will cause the bracket 70 to be shifted with the cross bar 13. Due to the fact that the brackets 70 and 59 are united by the screw 61 and 5 nuts 62 and 64 these parts likewise will partake of the case shifting movement of the cross bar 13 and the carriage, whereas a corresponding movement of the anti-friction carrier 50 will be effected by the cross bar 13 engaging in the groove 56 therein. It follows therefore that all of these parts will maintain their correlation in either case position to which the carriage may be shifted.

In the present instance I provide two final stops 73 each secured to the cross bar 13 near an end thereof by a screw 74. Each of these stops has two arms 75 that coat with an edge of the guide plate 47 to limit the movement of the carriage. By removing one of the stops 73, the screw 61 and 20 the brackets 59 and 70 the carriage may be moved endwise off the machine.

It will be understood that the screw 61 and nuts 64 and 62 provide means for effecting relative adjustments between different parts with 25 which they are associated.

It will be seen that the carriage has a two-way movement one being a case shifting movement and the other a movement in the direction of its travel; that the support 46 though adjustable is 30 fixedly held in any position to which it may be adjusted and that the anti-friction bearing rollers 49, 57 and 68 are in the nature of auxiliary rollers and are employed in addition to the rollers 16 by which the carriage is supported.

It will be observed, moreover, that in the present construction various parts are inclined to accord with the inclined shift of the platen, as distinguished from a vertical shift thereof in earlier No. 6 Remington noiseless machines.

While I have described in detail the means whereby the carriage and the supporting means therefor in the rear of the printing point may be bodily adjusted as a single unit fore and aft of the machine, it should be understood that any 45 suitable means may be employed for this purpose.

Various changes may be made in the construction, and certain parts thereof may be employed without others, without departing from my invention as it is defined in the accompanying 50 claims.

What I claim as new and desire to secure by Letters Patent is:

1. In a typewriting and like machine, the combination of a carriage that has a two-way movement, one being a case shifting movement and the other a traveling movement, a platen carried by said carriage, a fixedly held support that extends up in the rear of the platen and back of the printing center to resist the thrust of the type bars against the platen, the usual anti-friction rollers by which the carriage is supported in its traveling movement, a cross bar carried by the carriage intermediate the carriage and said support, and auxiliary anti-friction rollers that 60 65 coat with said cross bar on the front and rear edges thereof, the auxiliary rollers that coat with the rear edge of the cross bar being interposed between said bar and said support.

2. In a typewriting and like machine, the combination of a carriage that has a two-way movement, one being a case shifting movement and the other a traveling movement, a platen carried by said carriage, a fixedly held support that extends up in the rear of the platen and back of the printing center to resist the thrust of the 70 75

type bars against the platen, an anti-friction roller carrier that is shiftable with the carriage in the case shifting movements thereof but relatively to which the carriage is movable in the direction of its travel, and anti-friction rollers carried by said carrier and bearing against said support to afford an easy case shifting movement of the carriage relatively to said support. 5

3. In a typewriting and like machine, the combination of a carriage that has a two-way movement, one being a case shifting movement and the other a traveling movement a platen carried by said carriage, a fixedly held support that extends up in the rear of the platen and back of the printing center to resist the thrust of the type bars against the platen, an anti-friction roller carrier that is shiftable with the carriage in the case shifting movements thereof but relatively to which the carriage is movable in the direction of its travel, anti-friction rollers carried by said carrier and bearing against said support to afford an easy case shifting movement of the carriage relatively to said support, and a second set of anti-friction rollers carried by said carrier and with which the carriage coacts to afford an easy 20 25 travel thereof.

4. In a typewriting and like machine, the combination of a carriage that has a two-way movement, one being a case shifting movement and the other a traveling movement, a platen carried by said carriage, a fixedly held support that extends up in the rear of the platen and back of the printing center to resist the thrust of the type bars against the platen, an anti-friction roller carrier that is shiftable with the carriage in the case shifting movements thereof but relatively to which the carriage is movable in the direction of its travel, anti-friction rollers carried by said carrier and bearing against said support to afford an easy case shifting movement of the carriage 30 35 40 45 50 55 60 65 70 75 80 85 90 95 100 105 110 115 120 125 130 135 140 145 150 155 160 165 170 175 180 185 up in the rear of the platen and back of the printing center to resist the thrust of the type bars against the platen, a grooved anti-friction roller carrier, a cross bar on the carriage that is received 5 in the groove in the carrier and causes the latter to receive a case shifting movement with the carriage but affords a traveling movement of the carriage relatively to said carrier, a set of anti-friction rollers carried by said carrier and bearing 10 against said support, and a second set of anti-friction rollers carried by said carrier and against which said cross bar bears.

7. In a typewriting and like machine, the combination of a carriage that has a two-way movement, one being a case shifting movement and the other a traveling movement, a platen carried by said carriage, a fixedly held support that extends up in the rear of the platen and back of the printing center to resist the thrust of the type bars 15 against the platen, a grooved anti-friction roller carrier, a cross bar on the carriage that is received in the groove in the carrier and causes the latter to receive a case shifting movement with the carriage but affords a traveling movement of the carriage relatively to said carrier, a set of anti-friction rollers carried by said carrier and bearing 20 against said support, the axes of said rollers being horizontally disposed and aiding in effecting an easy shift of the carriage in its case shifting movements, and a second set of anti-friction rollers carried by said carrier and against which said cross bar bears, the axes of said last mentioned rollers being disposed at right angles to the axes 25 of the first mentioned rollers and coacting with said cross bar on opposite sides thereof.

which said cross bar bears, and manually controlled means for effecting a simultaneous adjustment of said support, carriage and carrier as a single unit fore and aft of the machine.

8. In a typewriting and like machine, the combination of a carriage that has a two-way movement, one being a case shifting movement and the other a traveling movement, a platen carried by said carriage, a fixedly held support that extends up in the rear of the platen and back of the printing center to resist the thrust of the type bars 5 against the platen, a grooved anti-friction roller carrier, a cross bar on the carriage that is received in the groove in the carrier and causes the latter to receive a case shifting movement with the carriage 10 but affords a traveling movement of the carriage relatively to said carrier, a set of anti-friction rollers carried by said carrier and bearing against said support, the axes of said rollers being horizontally disposed and aiding in effecting an 15 easy shift of the carriage in its case shifting movements, and a second set of anti-friction rollers carried by said carrier and against which said cross bar bears, the axes of said last mentioned rollers being disposed at right angles to the axes 20 of the first mentioned rollers and coacting with said cross bar on opposite sides thereof.

JOSEPH PHELPS.
